UNITED STATES PATENT OFFICE.

ELVIN TILTON, OF WHEELING, WEST VIRGINIA, ASSIGNOR TO HIMSELF, JOSEPH M. DU BOIS, AND SAMUEL G. CROW, BOTH OF BELLAIRE, OHIO, AND C. MONROE WATSON, OF WHEELING, WEST VIRGINIA.

WELL REAMER.

Application filed March 14, 1922. Serial No. 543,567.

To all whom it may concern:

Be it known that I, ELVIN TILTON, a citizen of the United States, residing at Wheeling, in the county of Ohio and State 5 of West Virginia, have invented a new and useful Improvement in Well Reamers, of which the following is a specification.

This invention relates to a reamer for cleaning out and enlarging the lower uncased portion of an oil well or the like so 10 that a freer flow of oil or other fluid may be produced.

A general object of the invention is to provide a reamer having cutting arms 15 which may be closed inward toward each other for lowering the reamer down or raising it from a well; and which may be opened progressively during a reaming operation so that they are at all times in 20 contact with the walls of the hole in the producing portion of the well as such hole is enlarged by the reaming operation.

A more specific object of the invention is to provide a reamer embodying means 25 which act both positively and automatically to force the arms of the reamer outwardly during the operation of cleaning and enlarging the hole.

Another specific object of the invention 30 is to provide a reamer in which all the parts are sturdy and capable of satisfactory operation at all times, so that the reamer stands up in service and operates unfailingly.

Another specific object of the invention 35 is to provide a reamer head for receiving the pivoted cutting arms which is not only sturdy in construction and provides strong and smooth bearings for the arms, but 40 which may readily be taken apart and put together for replacement of bushings or for repairs to the arms or their cutters.

In the accompanying drawings Figure 1 is a front elevation of the reamer, showing 45 the cutting arms thereof in extended or operating position; Figure 2 is a front elevation of the reamer, showing the arms in their inward or collapsed position; Figure 3 is a detail view of one of the cutting 50 arms of the reamer, showing the arm in front elevation; Figure 4 is a detail of the arm, showing the same in side elevation; Figure 5 is a top plan view of the reamer

head; Figure 6 is a vertical section through the reamer head on the line 6—6 Figure 5 55 showing the bushings and the trunnions of the cutting arms of the reamer in position therein; Figure 7 is a side elevation of the reamer head; Figure 8 is a detail elevation of the double cam for spreading the cutting 60 arms of the reamer; Figure 9 is a top plan view thereof; Figure 10 is a plan view of one of the pricker wheels or cutters of the reamer; Figure 11 is a vertical section through one of the end cutters of the cutting 65 arms of the reamer; and Figure 12 is a vertical section through the retaining nut for securing such end cutter in position on the cutting arm.

In the drawings the reference numeral 70 1 designates the cutting arms of the reamer, which are pivotally mounted in the reamer head 2 and are spread by means of the operating cam 3.

Surrounding each of the arms 1 is a 75 sleeve 4 upon which are mounted the pricker wheels or cutters 5, separated by washers 6. As shown, these pricker wheels or cutters 5 are of disk shape and provided with cutting teeth 7. Each 80 of the arms 1 is provided with an end cutter 8 of greater length than the majority of the cutters of the arm, which has at the extremity thereof a recess 9 in which fits a retaining nut 10 arranged to engage a 85 screw-threaded portion 11 at the extremity of the arm 1. It will be understood that the pricker wheels 5 are free to rotate on the bushing 4 of each of the arms, so that in use of the device they roll along the material which is being cut by the reamer. Because of the engagement of the retaining 90 nut interiorly of the end cutter, the means on both arms for retaining the cutter in position are protected during the use of the 95 reamer and the arms are rendered effective for cutting throughout their entire length.

The reamer head 2 is of novel construction, and is particularly designed to securely hold the cutting arms in pivoted relation thereto, while permitting such cutting arms to be readily removed from and replaced in the reamer head. For this purpose the reamer head 2 is divided horizontally on the line a—a to form two matching 100 portions 2^a and 2^b. Both of these portions

are provided with matching recesses forming the rectangular bearing seats 12, and are mutually secured by means of bolts 13 passing through both portions of the head. 6 Both members of the reamer head are cut away adjacent the bearing seats 12 to provide squared spaces 13^a for the reception of the upper extremities of the reamer arms 1. Fitting in the bearing seats 12 are externally squared bushings 14 in which lie the trunnions 15 carried by the reamer arms 1.

In assembling these parts of the device the reamer head 2 is separated, the trunnions 15 of the arms are inserted in the 15 bushings 14 and the bushings placed in position in the bearing seats 12. The parts 2^a and 2^b of the head may then be fastened together by means of the bolts 12.

It will be readily appreciated that this 20 form of head provides means for pivoting the arms of the reamer which are strong, which permit free swinging of the arms, and which also permit ready attachment of the arms to the head and ready removal of the 25 arms therefrom.

Both the reamer head 2 and operating cam 3 are carried by a short shaft 16, which passes through and is freely rotatable in a vertical orifice 17 in the reamer head, and 30 which has the cam 3 disposed adjacent its lower extremity. As shown, the cam 3 is formed integral with the shaft 16, but it may if so desired be secured thereto in any suitable manner. In order that the shaft 16 35 may be rotated in using the reamer it is joined with tubing 18, which extends to the mouth of the well and may be rotated by any mechanism adapted to that purpose. As shown, such connection is by means of a 40 step-up connection 19 to which the shaft 16 is screw-threaded and which is in turn screw-threaded to the tubing 18.

When the reamer is lowered into the well the arms are in their inward or collapsed position, shown in Figure 2 of the drawings, 45 so that the cross sectional area of the reamer as a whole is relatively small and it may be passed downwardly through the well casing. The cutting arms 1 of the reamer remain in 50 this position until they are forced outwardly by the action of the cam 3 caused by rotation of the tubing 19.

The cam 3 comprises a central portion 20 which, as shown, is a continuation of the 55 shaft 16, and oppositely curved arms or wings 21 and 22 extending in opposite direction from such central portion 20. Each of the wings 21 and 22 has a longer convex surface 20^a and a shorter concave surface 60 20^b. When the cam 3, and its carrying shaft 16 are not being rotated by means of tubing 19, the cutting arms 1 lie in their inward or collapsed position on the concave sides 20^b of the wings 21 and 22. When the tubing 19 is rotated, the cam 3 is rotated there-

with, and bearing against the cutting arms 1, serves to rotate the reamer head 2 and cutting arms 1 for causing the cutting arms to exert a cutting action on the walls of the hole in the well. As the tubing 19 and cam 70 3 are rotated the cutting arms 1 ride outwardly along the convex surfaces 20^a of the wings of the cam, and are forced thereby into intimate contact with the walls of the hole. 75

The outward spread of the arms 1 may be limited and regulated by means of set screws 23; which are screw-threaded in the upper member 2^a of the reamer head, and may be caused to project the desired distance to contact and check the spread of the cutting arms. This prevents centrifugal force from causing the arms 1 to swing outwardly out of contact with the cam 3 when the reamer is used in a shot hole in which cavities of considerable extent may occur. 85

In order that the action of the cam 3 may operate to spread the arms uniformly and positively up to the limit of spread for which they are set, the arms 1 carry rollers 90 24 with which the cam 3 is in direct contact, and the cam is particularly designed to produce the spreading action in all angular positions of the arms relatively thereto. 95

It is to be observed in this connection that the wings 21 and 22 of the cam are not only curved in a horizontal plane, but that each wing is also curved in a vertical plane so that, as each of the arms moves outwardly on a wing the vertical contour line of the wing remains parallel to the longitudinal axis of the arm. In order that the convex surfaces 20^a of each of the wings 21 and 22 may lie in such contact with the rollers 23 as to exert an upward and outward force 100 against the arms at all times, these surfaces are bevelled progressively outward from the central portion 20 of the cam. As shown, the angle of the bevel of such surfaces 23 increases from approximately one degree adjacent the central portion 20 of the cam to an angle of approximately forty-one degrees adjacent the outer extremity of each arm. 105 110

It will thus be seen that the cam 3 exerts at all times a positive force holding the cutting arms to their work; and that it prevents either of the arms from being knocked inwardly if it should strike any projection in the wall of the hole, as the positive action of the cam during its rotation immediately checks any such tendency. 115

When rotation of the shaft 16 and cam 3 is suspended the cutting arms 1 are carried inwardly by their own weight, so that they 120 ride along the arms of the cam into the position shown in Figure 2 of the drawings. With the arms in this position the reamer as a whole may be readily withdrawn from the well. 125 130

A number of previously designed well reamers have comprised pivoted arms arranged to spread progressively during the cleaning and enlargement of a hole. Several 5 of such reamers have depended upon centrifugal force to effect the necessary spreading of the arms, while others have embodied special means operating positively to effect such spreading, and operating to fulfill this 10 purpose either wholly of themselves or in conjunction with the centrifugal force produced by rotation of the pivoted arms. As a general rule reamers of the latter type are provided with spreading means which are 15 operated to spread the arms either by contact of the reamer with the bottom of the well or by long rods extending to the well mouth. When the relatively great depth of the average oil well and the strain to which 20 reamers are put are considered, it will be seen that such devices are inherently incapable of giving the most satisfactory results possible.

It is to be particularly noted that the 25 arms of the reamer described and claimed herein are not only spread automatically by the rotation of the means supporting the reamer, but that they are also spread by means which act positively upon them to effect such spreading. It is further to be noted that all the parts are sturdy and fully capable of performing their functions without likelihood of breakage or distortion under the stresses to which they are subjected. 30 The reamer may be used to clean and enlarge the drilled lower extremities of wells with equally advantageous effect as when the well has been shot. This is because the cutting arms are held positively to their 35 work and because they cut equally well in any angular position.

As the device described above is susceptible of numerous modifications without departing from the spirit of the invention 40 which it embodies, the scope of such invention is to be restricted only by the limitations contained in the claims appended hereto.

What I claim is:

1. In a reamer for oil wells and the like 45 a plurality of pivoted cutting arms, and a rotatably mounted cam having a plurality of operating wings arranged to act upon said arms and so curved in both a horizontal and a vertical plane that the contour lines of their operating faces lie parallel to the longitudinal axis of the cutting arms in all angular positions thereof.

2. In a reamer for oil wells and the like 50 a plurality of pivoted cutting arms, rollers on said arms; and a rotatably mounted cam having a plurality of wings arranged to bear directly against said rollers, said wings being curved in both a horizontal and a vertical plane so that the contour lines of their

operating faces lie parallel to the longitudinal axis of the cutting arms, and such operating faces being bevelled at a gradually increasing angle outwardly of the wings so that they exert a force tending to force the 70 cutting arms upwardly and outwardly in all angular positions of the cutting arms.

3. In a reamer for oil wells and the like 75 a plurality of pivoted cutting arms, and a rotatably mounted cam having a plurality of operating wings arranged to act upon said arms and so curved in both a horizontal and a vertical plane that the contour lines of their operating faces lie parallel to the longitudinal axis of the cutting arms in all 80 angular positions thereof, and adjustable means for limiting the spreading of said cutting arms.

4. In a reamer for oil wells and the like 85 a plurality of pivoted cutting arms, rollers on said arms; a rotatably mounted cam having a plurality of wings arranged to bear directly against said rollers, said wings being curved in both a horizontal and a vertical plane so that the contour lines of their 90 operating faces lie parallel to the longitudinal axis of the cutting arms, and such operating faces being bevelled at a gradually increasing angle outwardly of the wings so that they exert a force tending to force the 95 cutting arms upwardly and outwardly, in all angular positions of the cutting arms, and adjustable means for limiting the spreading of said cutting arms.

5. In a reamer for oil wells and the like 100 a plurality of pivoted cutting arms, and a rotatable member so arranged that by its single rotation it serves to simultaneously swing said arms about a vertical axis and spread the same.

6. In a reamer for oil wells and the like 105 a plurality of pivoted cutting arms, and a cam mounted for rotation and having a plurality of wings arranged to bear against said cutting arms to spread the same upon simple rotation of the cam.

7. In a reamer for oil wells and the like 110 a plurality of pivoted cutting arms, and a cam mounted for rotation and having a plurality of wings arranged to bear against said cutting arms to simultaneously spread and swing the same about a vertical axis upon simple rotation of the cam.

8. In a reamer for oil wells and the like 115 a plurality of pivoted cutting arms, and a cam mounted for rotation and having a plurality of wings arranged to bear against said cutting arms to spread the same upon simple rotation of the cam, the operating surfaces of said cam wings being bevelled at an angle increasing progressively outwardly of said arms.

9. In a reamer for oil wells and the like 120 a plurality of pivoted cutting arms, and a cam mounted for rotation and having 125

- 5 a plurality of wings arranged to bear against said cutting arms to simultaneously spread and swing the same about a vertical axis upon simple rotation of the cam, the 10 operating surfaces of said cam wings being bevelled at an angle increasing progressively outwardly of said arms.
- 10 13. In a reamer for oil wells and the like 30 a plurality of pivoted cutting arms, rollers mounted on said arms concentrically therewith, and a cam mounted for rotation and having a plurality of wings arranged to bear against said rollers to spread said 35 cutting arms upon simple rotation of the cam, the operating surfaces of said cam wings being bevelled at an angle increasing progressively outwardly of said arms.
- 15 14. In a reamer for oil wells and the like 40 a plurality of pivoted cutting arms, and a cam mounted for rotation and having a plurality of wings arranged to bear against rollers on said arms to simultaneously spread and swing said arms about 45 a vertical axis upon simple rotation of the cam, the operating surfaces of said cam wings being bevelled at an angle increasing progressively outwardly of said arms.
- 15 12. In a reamer for oil wells and the like a plurality of pivoted cutting arms, rollers mounted on said arms concentrically therewith, and a cam having a plurality of wings arranged to bear against said rollers to simultaneously swing said cutting arms about a vertical axis and spread the same upon simple rotation of the cam.

In testimony whereof, I hereunto set my hand.

ELVIN TILTON.
